UNITED STATES PATENT OFFICE.

JOHN CASPER ARENSBERG, OF UNIONTOWN, PENNSYLVANIA, ASSIGNOR TO
THE THOMPSON GLASS COMPANY, LIMITED, OF SAME PLACE.

DESIGN FOR A PEPPER-POT OR SALT-SHAKER.

SPECIFICATION forming part of Design No. 20,042, dated July 22, 1890.

Application filed June 25, 1890. Serial No. 366,722. Term of patent 3½ years.

To all whom it may concern:

Be it known that I, JOHN CASPER ARENSBERG, a citizen of the United States, residing at Uniontown, in the county of Fayette and State of Pennsylvania, have invented a certain new Design for Pepper-Pots or Salt-Shakers; and I do hereby declare the following to be a full, clear, and exact description of the invention, reference being had to the accompanying drawings, which form part of this specification.

My invention has relation to designs for pepper-pots or salt-shakers; and it consists in the novel shape and configuration herein-after described, and illustrated in the accompanying drawings.

In carrying out my invention I form the pepper-pot, salt-shaker, or other vessel in the shape substantially and in imitation of a trumpet, the perforated top of the vessel being at the small end, and the vessel standing on the wide base, which corresponds to the bell-mouth of the trumpet.

In the accompanying drawings, Figure 1 is a side elevation of a vessel made according to

my novel design, and Fig. 2 is a modified form of the same.

A designates the enlarged base of the vessel, corresponding as nearly as possible in appearance to the bell-mouth of a trumpet. B designates the tapering body, and C the perforated top, taking the place of the mouth-piece. D designates a handle, and E ornamental bands which surround the vessel above and below the handle D.

In Fig. 2 of the drawings the general shape and configuration of the vessel are the same as shown in Fig. 1, but the ornamental bands and the handle are omitted.

Having described my design, I claim—

The design for a pepper or saltshaker, consisting in a conventional representation of a trumpet, as herein shown and described.

In testimony that I claim the foregoing I have hereunto set my hand this 3d day of June, 1890.

JOHN CASPER ARENSBERG.
